(57) **CLAIM**

The ornamental design for a sign for vehicles, as shown and described.

DESCRIPTION

FIG. 1 is an isometric view of a sign for vehicles, showing our new design;

FIG. 2 is a front elevational view;

FIG. 3 is a rear elevational view;

FIG. 4 is a top plan view;

FIG. 5 is a bottom plan view;

FIG. 6 is a right-hand side elevational view;

FIG. 7 is a left-hand side elevational view;

FIG. 8 is an isometric view of another embodiment of the sign for vehicles, showing our new design;

FIG. 9 is a front elevational view;

FIG. 10 is a rear elevational view;

FIG. 11 is a top plan view; and

FIG. 12 is a bottom plan view.

FIG. 13 is a right-hand side elevational view; and,

FIG. 14 is a left-hand side elevational view.

In the drawings, the broken lines are for illustrative purposes only and form no part of the claimed design.
